DESIGN FOR AN ELECTRIC CONTROLLING DEVICE

Alvin W. Krieger, Milwaukee, Wis., assignor to
Cutler-Hammer, Inc., Milwaukee, Wis., a cor-
poration of Delaware

Application July 22, 1937, Serial No. 70,575

Term of patent 14 years

To all whom it may concern:

Be it known that I, Alvin W. Krieger, a citizen of the United States and a resident of Milwaukee, in the county of Milwaukee and State of Wisconsin, have invented a new, original, and ornamental Design for an Electric Controlling Device, of which the following is a specification, reference being had to the accompanying drawing, forming part thereof.

Figure 1 is a front elevational view of an electric controlling device incorporating my new design.

Fig. 2 is a top plan view of the electric controlling device.

Fig. 3 is a side elevational view thereof.

Fig. 4 is a perspective view of the electric controlling device.

I claim:

The ornamental design for an electric controlling device, substantially as shown.

ALVIN W. KRIEGER.
